UNITED STATES PATENT OFFICE.

JACOB C. HEINTZ, OF BUFFALO, NEW YORK.

RAILWAY-TIE.

No. 874,193.

Specification of Letters Patent. Patented Dec. 17, 1907.

Application filed April 1, 1907. Serial No. 365,849.

To all whom it may concern:

Be it known that I, JACOB C. HEINTZ, a citizen of the United States, residing at Buffalo, in the county of Erie and State of New York, have invented certain new and useful Improvements in Railway-Ties, of which the following is a specification.

This invention relates to improvements in railway ties, and the object is to provide substantial but yet light ties of metal having wooden blocks to which the rails may be secured in the same manner as they are now secured to the ordinary wooden tie, and to so construct said tie that the wooden blocks may be readily removed therefrom, but in which the blocks will be held securely in position without the use of spikes or other similar fastening devices.

In the drawing, I have illustrated my improved tie in perspective, one of the wooden blocks being removed and the other shown in position with a portion of a rail attached thereto.

Referring now more particularly to the drawing, 1 designates the base-plate of the tie, which may be of the same width and length as the ordinary wooden tie now in general use, and of any desired thickness. Formed near each end of the base-plate on the upper side thereof, is a box or seat 2 open at both ends, said boxes or seats being connected by a centrally-disposed web-portion 3, and having web-portions 4 at their outer sides. The seats or boxes have their side-walls formed converging upon their inner surfaces with overhanging beveled portions 5 at their upper edges, to receive wooden blocks 6 of corresponding shape. These blocks are held from vertical displacement by the overhanging portions 5 of the seats, and from longitudinal displacement by setting the tie so that the smaller ends of the seats are in the direction of travel of the train, whereby the tendency will be to force the blocks forward and wedge them securely in the seats. Thus said blocks are securely held in the seats without the use of spikes or other similar securing devices, and at the same time may be quickly removed by driving them out by a blow on the small ends thereof, the boxes or seats being open at that end for this purpose. These blocks act as a cushion in the same manner as an ordinary wooden tie, and yet at the same time afford an attaching surface to which the rails may be readily spiked, which may be quickly and

easily replaced by removal from the seats and replacement by new blocks. Further, these blocks not being spiked to the seats of the tie or otherwise rigidly secured thereto, do not interfere with its contraction and expansion.

The tie may be secured in a cement roadbed or used with the stone or other roadbed which may now be employed and held just as securely as the present wooden tie.

For use on a single track road, the tie may be formed with one of its seats having its smaller end disposed on one side thereof, and the other seat with its smaller end disposed on the opposite side of the tie.

Having thus fully described my invention, what I claim as new and desire to secure by Letters Patent of the United States, is:

1. A metallic railway tie comprising a base, seats carried thereby having converging side-walls, and wooden rail-supports fitting in said seats.

2. A metallic railway tie comprising a base, seats carried thereby open at each end and having converging side-walls, and wooden rail-supports fitting in said seats.

3. A metallic railway tie comprising a base, seats carried thereby open at both ends and having converging side-walls, wooden rail-supports fitting in said seats, and means carried by said seats for preventing vertical displacement of the rail-supports.

4. A metallic railway tie comprising a base, seats carried thereby open at both ends and having converging side-walls with overhanging upper portions, and wooden rail-supporting blocks shaped to fit in said seats.

5. A metallic railway tie comprising a base, seats carried thereby, and wooden rail-supporting blocks fitting in said seats, the several parts being so constructed that tendency of the rails to longitudinal movement by the travel of the train will wedge said blocks in the seats.

6. A metallic railway tie comprising a base-plate, seats or boxes formed at each end thereof open at both ends and formed with converging side-walls having overhanging beveled upper portions, and wooden rail-supporting blocks shaped to fit in said seats.

In testimony whereof I affix my signature in presence of two witnesses.

JACOB C. HEINTZ.
